UNITED STATES PATENT OFFICE.

PETER ROTH, OF NEW SALEM, NORTH DAKOTA.

CLOTHES-RACK.

1,264,864.

Specification of Letters Patent. Patented Apr. 30, 1918.

Application filed June 27, 1917. Serial No. 177,346.

To all whom it may concern:

Be it known that I, PETER ROTH, a citizen of the United States, residing at New Salem, in the county of Morton and State of North Dakota, have invented new and useful Improvements in Clothes-Racks, of which the following is a specification.

The present invention relates generally to clothes driers, and more particularly to that 10 class thereunder known as foldable clothes driers.

The primary object of the present invention resides in the production of a rack of the above stated character which is simple 15 in construction, strong, durable and efficient in use, and so designed to permit of the folding thereof in a simple and expeditious manner, and further when the rack is in a folded position occupies but a minimum 20 amount of space for the storage or transportation of the same.

Furthermore, I contemplate the provision of a rack of the above stated character embodying an extensible pivotally mounted 25 auxiliary frame, the spaced side bars of said frame presenting channels in which are movably supported rollers adapted, when the frame is swung to assume a horizontal position, to be adjusted in the channels of 30 the auxiliary frame, permitting the supporting of various articles of apparel.

With the above and other objects in view, the invention consists in the novel features, 35 details of construction and combination of parts which will hereinafter be more fully set forth, illustrated in the accompanying drawings and pointed out in the appended claims.

Figure 1 is a front elevation of the rack 40 suspended from a suitable support and shown in a folded position;

Fig. 2 is a perspective view of the rack in an open position;

Fig. 3 is a view similar to Fig. 2 showing 45 the auxiliary frame in an extended position; and

Fig. 4 is a transverse section taken on line 4—4 of Fig. 1.

Fig. 5 is a vertical sectional view.

Referring more particularly to the accompanying drawings, wherein is shown the preferred embodiment of the invention, the 50 rack as its entirety is denoted by the char-

acter 5 and embodying a main rectangular frame 6 including spaced parallel side rails 7 connected to one another through the medium of a lower cross rail 8 and an upper cross rail 9. Secured to the top surface of the upper cross rail 9 is a pair of spaced screw eyes 10 whereby the device generally 55 may be suspended from a suitable support A. 11 denotes a plurality of spaced hooks secured to the front face of the lower cross rail for supporting small articles of apparel. Arranged above and in parallelism 60 with the lower rail 8 is a cross bar 12, secured to the exterior face of the spaced side rails 7 through the medium of screws or the like fastening devices, indicated by the character 13 and the purpose of this cross bar 65 70 will be fully brought out as the description of the invention is proceeded with.

Supported within the main frame for vertical swinging movement is an auxiliary frame, indicated generally by the character 75 14 and preferably constructed of a pair of telescopically mounted channeled arms 15 embodying an inner section 16 and an outer section 17. The inner extremities of the inner section 16 are pivotally secured to the 80 confronting faces of the spaced side rails 7 of the main frame, through the medium of a nut and bolt connection 18, passing transversely through said rails and pivotally supporting the auxiliary frame at a point adjacent to the cross bar 12 and within the 85 main frame 6 for vertical swinging movement, and upon the auxiliary frame assuming an open position, the inner sections 16 of the frame will repose upon the cross bar 12 90 and prevent any undue downward movement of said frame when subjected to the weight of the articles of apparel to be dried.

Now assuming the frame is swung in a downward and outward direction and supported in a horizontal position, the channeled arms of the outer section are pulled 95 outwardly until the proper extension of the auxiliary frame is obtained, after which the loosely mounted clothes supporting members 19, mounted in the channels of the outer section 16, are properly adjusted within the channels at suitable spaced intervals, to permit of the various articles of apparel to be dried to be hung thereon. These clothes 100 105 supporting members embody a plurality of

rollers having dove-tailed pintles 20 to conform to the cross sectional contour of the channels. In other words, the channeled arms 15 of both the inner and outer sections 5 are formed with contracted open ends 21, provided by converging the side walls 22 of said arms in a direction toward the open ends thereof, consequently, the side walls of the outer section will frictionally engage 10 with the walls of the inner section to suffice in retaining the outer section, at all times in a proper adjusted position. The outermost roller 23 of the clothes supporting members is stationarily secured to the free extremities 15 of the channeled arms 15 of said outer section through the medium of screws 24, and serving to connect the spaced channeled arms forming the outer section of the frame to one another. As the outer section of the 20 auxiliary frame is telescoped within the channeled arms forming the inner section thereof, and the frame swung to an upright vertical position, the clothes supporting members 19 are slid in the channeled arms 25 in a direction toward the fixed roller 23, to permit of the rollers being supported against movement within the channeled arms by the engagement of the lowermost roller 25 in the resilient keeper 26 secured medially of the 30 upper cross rail 9 of the main frame.

From the foregoing description, taken in connection with the accompanying drawings, the advantages of construction and the method of operation will be readily apparent to those skilled in the art to which the invention relates, and while I have described the principles of operation of the invention, together with the device which I now consider to be the best embodiment thereof, I 35 desire to have it understood that the device shown is merely illustrative, and that such 40

changes may be made when desired as are within the scope of the appended claims.

What is claimed as new, is:—

1. A foldable clothes drier embodying a 45 main frame adapted to be suspended from a suitable support, an auxiliary frame pivotally mounted within the main frame for a vertical swinging movement, said auxiliary frame comprising a plurality of telescopically mounted sections, and a plurality of clothes supporting members slidably mounted in one of the sections of the auxiliary frame.

2. A foldable clothes drier embodying a 50 main frame adapted to be suspended from a suitable support, an auxiliary frame pivotally mounted within the main frame for a vertical swinging movement, said auxiliary frame comprising a plurality of telescopically mounted sections, and a plurality of clothes supporting members movably mounted in one of the sections of the auxiliary frame, and means secured to the main frame 55 with which the clothes supporting members engage and adapted to hold the auxiliary frame and clothes supporting members in collapsed form.

3. A foldable clothes drier embodying a 60 main frame, an extensible channeled auxiliary frame pivotally connected within the main frame, a plurality of clothes supporting members slidably mounted in the channels of the auxiliary frame and means on the main frame with which the clothes supporting members engage upon the swinging of the auxiliary frame to a closed position for supporting both the latter and former in 65 collapsed position.

In testimony whereof I affix my signature. 70

PETER ROTH.
